HOT-AIR FURNACE.

Application filed August 13, 1927. Serial No. 212,782.

This invention relates to hot air furnaces as used for the heating of homes and buildings generally and while the invention contemplates any source of heat in the fire box 5 it is particularly concerned with a gas-fired hot air furnace. The objects of the invention being to realize the greatest amount of heat from the fuel used, a furnace of compact form requiring little head room, and 10 special furnace construction to attain the objects as will appear in the drawings and specification hereto.

In the drawings Fig. 1 is a longitudinal section of one form of our furnace, Fig. 2 is 15 an end elevation of the furnace. Fig. 3 is an enlarged sectional drawing showing the pipe connections between the fire box and the air heating drums.

Figs. 4 and 5 are respectively longitudinal 20 section and end views of a modified form of our invention.

Briefly described our invention comprises a novel arrangement of furnace elements in horizontal extension whereby the height of 25 the furnace is greatly reduced, and whereby the heated gases flow from the fire in one general horizontal direction toward the stack, while the cool air to be heated flows through the furnace in the opposite direction, thereby creating a counter-flow of hot 30 gases and air and thus bringing the cool air gradually toward the more highly heated portion of the furnace and realizing the greatest extraction of heat from the heated 35 elements of the furnace by bringing the coolest air first into contact with the least heated portions of the furnace.

The invention also includes special furnace elements for more efficiently carrying 40 out the counter-flow of gases and transfer of heat.

In the drawings, Figs. 1 to 3 our furnace comprises a sheet metal body or casing 1 which may advantageously be covered with 45 any suitable heat insulation (not shown) and which body takes the form of an elongated horizontally extending shell of almost any desired cross section, but preferably with rectangular flat base 2 as shown in Fig. 50 2 and with a semi-cylindrical top as shown, though it may be lower.

At the forward end of the horizontal shell is a cylindrical dome 4 closed on top

and from the side wall of which extend the usual hot air pipes 5 which convey the hot air to the rooms to be heated. 55

The shell is split on a horizontal line, preferably at the juncture of the curved top with the vertical sides of the body and joined by bolt flanges 6 so that the upper half can 60 be lifted from the lower half.

Within the shell at the forward end is arranged a fire pot or box 7 preferably mounted on a foundation 8 and which box 65 houses a burner 9 which may be for liquid or gaseous fuel as may be desired.

The burner pipe extends out of the furnace as shown and the space above the pipe is closed by an upwardly swinging door 10, while the space below is preferably fitted 70 with an air shutter door 11 for controlling the amount of free air flowing around the burner.

The fire box is preferably arranged with an upper wall slanting generally upwardly 75 and rearwardly to a point just above the hot gas outlet 12, and from the hot gas outlet extends a horizontal flue terminating in a stack 13 outside of the shell.

The horizontal flue comprises a series of 80 short sections of pipe 14 in horizontally staggered relation secured to and suspending a series of air heating drums 15, 15', 15''.

These drums are substantially flat and preferably elliptical boxes supported vertically from the pipes as shown, the pipes entering the flat sides of the boxes close to the upper ends of the same with the inlet and outlet pipe of each box laterally offset and separated by a baffle plate 16 which connects 90 the flat walls of the box and terminates short of bottom wall of the box so that the hot gases entering at the top at one side of the baffle must descend in one-half of the box and rise in the adjacent half for exit to the 95 continuation of the flue on their way to the stack.

The flat drums preferably stand at various angles from the flue as shown in Fig. 2 and may even project upward as indicated at X 100 in Fig. 1, the object being to secure as much turbulence to the gases as possible.

In practice these air heating drums 15 and the fire box 7 are preferably made of thin cast iron, and the pipe sections are cast into 105 one of the members as at A in Fig. 3 and

screwed into the adjacent member as at B in Fig. 3, thus each pipe is virtually an integral portion of one of the cast members.

Extending across the casing or furnace shell are baffle plates 17, 18, 19, 20. These plates take alternate positions between the air heating drums (the fire box 7 also being an air heating drum), plates 18 and 20 extending from the base to about the center 10 of the horizontal flue pipes 14 and being notched or perforated to support them and the attached drums, while plates 17 and 19 extend from the roof of the shell downward and are similarly notched for the pipes 14. 15 Plate 17 extends from the juncture of the dome 4 and shell 1 and is preferably curved as shown to maintain a substantially constant passage area for the ingress of fresh air to the furnace which flows along the 20 path indicated by the small arrows, entering first at the upper open portion of the rear end of the furnace and successively down and up over the several heating drums (which through their flat sides act as baffles) and finally up around the fire box 7 and into the dome 4 for distribution.

While the fresh air is thus entering the stack end of the furnace the hot gases are flowing in an opposite direction through the 25 staggered pipes 14 and baffled drums 15, thus finally passing the increasingly heated fresh air over the hottest of the heated elements before distribution to the hot air pipe.

It should be noted that while we show 30 three drums 15, 15', 15'' for heating the incoming air, any number may be used, the cold air intake being at the top half of the rear end of the furnace for 1-3 or 5 drums and at the bottom half for 2-4 or 6 drums, 35 as will readily be observed, or the fresh air inlet may be at the side or top of the furnace casing with the baffles suitably arranged to cause the counter-flow of air and hot gases.

40 By the construction described, any expansion of the heated parts is taken care of by a slight sliding of the pipes 14 along their seats in the baffles 18 and 20 without putting any strain upon the joints, and all heating 45 elements may be inserted or lifted out as a unit upon removing the upper half of the shell 1.

In Figs. 4 and 5 a modification of our furnace is shown in which the shell 21 is of 50 cylindrical form and, as shown in Fig. 3 is supported by legs 22, and the air heating drums 23 are arranged horizontally in overlapping relation with the end of one secured by a pipe nipple directly to the other.

60 In Figs. 4 and 5 but two of the drums are

shown, the first one overlying and resting on the fire box 24 and the last one being supported on pipe stands 25, with the stack 26 extending vertically from the last one. Any number of drums in the relation shown may 65 be used, and baffles 27-28 extend across the shell so as to direct the incoming fresh air in direction of the arrows to produce the counter-flow of hot and cold gases as described for Fig. 1, but in this case the cold 70 air intake is at the lower part of the rear end of the shell, and of course the cold or fresh air intake may in either construction communicate directly with the outer air or with a return duct from the rooms to be 75 heated as done with other types of hot air furnaces.

From the showing of Figs. 1 and 4 it will be seen that the invention is susceptible of modifications while operating in substantially identical manner and any such modifications as come within the spirit of the invention are intended to be covered in the appended claims.

We claim:

1. In a hot-air furnace having a hot-air outlet, a fire-box provided with a flue extending in a lateral direction therefrom, a heating drum connected to and suspended from said flue, and means to cause a flow of 90 air to be heated about said drum and thence about said fire-box and toward said hot-air outlet.

2. In a hot-air furnace, a fire-box provided with a flue extending in a lateral direction therefrom, a plurality of heating drums connected to and spaced along said flue, and means whereby air to be heated is caused to flow about the flue and drums in a direction generally opposite to the flow of hot gases 100 within the flue.

3. In a hot-air furnace, a fire-box provided with a flue extending in a lateral direction therefrom, a plurality of heating drums connected to and spaced along said flue, and means whereby air to be heated is caused to flow about the flue and drums and thence about said fire-box.

4. In a hot-air furnace of the character described, a fire-box, a flue extending substantially in a horizontal direction from the upper portion of the fire-box, a plurality of box-like heating drums connected to and hanging vertically from said flue and means for guiding air to be heated about the flue 110 and drums generally in direction of said fire box.
